EYELASH CURLER

Irwin E. Cohn, Merrick, N. Y., and Wilfred E. Tait,
Westport, Conn.

Application December 18, 1933, Serial No. 702,914

11 Claims. (Cl. 132—32)

The present invention relates to eyelash curler particularly adapted for feminine use in beautifying establishments and in the home.

Many devices for this purpose have been made but they all have proven impractical or cumbersome and difficult to handle and manipulate and have proven unsatisfactory in that frequently they would break or cut the hairs of the eyelash. They all included complementary rigid, though sometimes cushioned, jaws and invariably required considerable and maintained manual pressure to be applied to the device to produce the desired results.

Hence an object of the invention is the provision of an improved means for curling or bending the eyelashes and to overcome the above difficulties and one which can be very conveniently and easily applied to and removed from the lashes between the curling or forming elements, which are simple and easy to operate and which are extremely compact and of simple and economical construction.

A further object is to provide an eyelash curler, the handle of which may be firmly grasped in the hand and the thumb utilized to move one of the clamping members to or from the other.

Another object of the invention resides in the provision, in an instrument for curling lashes, of a movable resilient and stretchable clamping member adapted to be slid past a lip portion on the fixed clamping member to grip the eyelash therebetween and to retain said gripping engagement until manually released by withdrawal of the moving clamp member.

A further object is to provide, in an eyelash curler, a movable clamp member in the form of a close wound coil spring which may be covered by a yieldable and stretchable casing for the purpose of subjecting the eyelid of the user to a minimum of pull and abuse.

A further object is to provide in a device of the purpose, a rigid forming element and a cooperating resilient element both of which may be interlocated over an eyelash with constant though yielding pressure, and which may thus be retained on the lash without the application of manual pressure to properly and effectively curl or bend the lashes.

In its general organization this device comprises a rigid curved forming element, and a cooperating resilient forming element, the rigid element being mounted on the end of a hollow handle, and the ends of the resilient element being anchored adjacent the ends of the rigid element, with the centre of the resilient element

engaged with a slide operable within the hollow handle and having a manipulating button extending through a slot in the handle, the rigid element having a forming or bending flange over which the resilient element interengages. 60

These advantageous features are accomplished by the novel and practical construction, combination and arrangement of parts hereinafter disclosed and illustrated in the accompanying drawing, constituting an essential part of the disclosure, and in which:

Fig. 1 is a front elevational view of a curler constructed in accordance with the invention and shown in the eyelash clamping position.

Fig. 2 is a side view thereof preparatory to 70 clamping.

Fig. 3 is a vertical cross sectional view of the instrument in the clamping position.

The device is preferably made of metal parts though other materials suitable for the purpose 75 may be employed.

A handle is provided which is preferably formed of the handle portion 5 and an extension 6 of the head portion 7. The portion 5 is preferably provided with flanged side and bottom portions 80 8 and riveted at 9 and 10 to the extension 6 to form a hollow 11 within the handle. For the purposes of strength and rigidity a reinforcing member 12 may be incorporated as shown.

The head 7 is preferably curved as shown to 85 the normal curvature of an eyelid and is provided with the opening 13 formed by the upright member 14, the arched clamping member 15 and the portion 16 adjacent the extension 6. The uprights 14 may be made rigid by providing portions 90 such as the angled extension 17.

The lower portion of the arched clamping member 14 is preferably formed with a lip portion 18 the purpose of which will be later made clear.

A movable clamp member 19 is provided in the 95 form of a close wound coil spring or any other resilient material anchored at its ends to the head as at 20 and this member, if a coil spring, is preferably covered by a resilient and stretchable casing, covering or sheath 21.

Movement of the clamp member 19 is effected through the medium of a slide member 22 fastened thereto at 23. The slide is provided with a slot 24 so the slide may be guided in its movements by the rivet 9 and is also provided with a 100 thumb engaging knob 25 at its end within the hollow 11, the shank 26 of which may be moved along the slot 27 formed in the members 6 and 12.

In operation the instrument is held in one hand and positioned in relation to the eye so the 110

eyelash touches the bottom or lip portion 18 of the fixed clamp member 15 as shown in Fig. 2. An upward push of the thumb against the knob 25 will, through the medium of the slide 22, cause 5 the clamping member 19 to first engage against the bottom of the eyelash and then to snap over the lip 18 to grip the hairs of the eyelash effectively between itself and the member 15. It will be noticed that at no time is there any movement 10 of the clamping member 15 and there cannot be, therefore, any pull on the eyelid, the eyelash being nicely and gently curled over the lip 18 and clamped. The clamping pressure need not be retained since the members will retain their 15 clamping position until a downward push on the knob 25 releases them.

While the drawing illustrates the slide as operating within the hollow 11 of the handle, it will be understood that, the handle may be made 20 solid and the slide 22 will then operate along the outside of the handle.

It will also be understood that the slide 22 might if desired, be altogether eliminated and in such case the thumb or finger of the user may be 25 utilized to manipulate the resilient clamping member 19.

From the foregoing it will be seen that a simple device for the purpose has been disclosed in the preferred form of its embodiment, but it is not 30 desired to restrict the details to the exact construction shown, it being obvious that changes, not involving the exercise of invention, may be made without departing from the scope of the appended claims.

35 Having thus described our invention, what we claim as new and desire to secure by Letters Patent, is:

1. An eyelash curler comprising a fixed clamp member, a resilient and stretchable movable clamp member and means to move one clamp member in 40 relation to the other.

2. An eyelash curler comprising a handle, a clamp member fixed thereto, a resilient and stretchable clamp member and means attached 45 thereto and associated with the handle to move the last mentioned clamp member to and from the other clamp member.

3. In an eyelash curler a fixed clamp member, a lip on the lower portion thereof, a resilient and stretchable clamp member, and means to removably engage the movable clamp member over the 50 said lip.

4. In an eyelash curler a fixed clamp member, a lip on the lower portion thereof, a resilient and 55

stretchable movable clamp member having its ends connected adjacent the ends of the fixed clamp members, and means whereby the movable clamp member may be moved to engage over the said lip.

5. In an eyelash curler a fixed curved and arched clamp member, a lip on the lower portion thereof, a resilient and stretchable movable clamp member and means to engage the movable clamp member over the said lip.

6. In an eyelash curler a fixed curved and arched clamp member, a lip on the lower portion thereof, a resilient and stretchable movable clamp member having its ends connected adjacent the ends of the fixed clamp members, and means whereby the movable clamp member may be moved to engage over the said lip.

7. An eyelash curler comprising a hollow handle, a curved and arched clamp member fixed thereto, a lip on the lower portion thereof, a resilient and stretchable movable clamp member having its ends connected adjacent the ends of the fixed clamp member, a slide attached to an intermediate portion of the movable clamp member and adapted to slide within the hollow of the handle and a knob adapted to be manually moved whereby the movable clamp member may be engaged over the said lip.

8. In an eyelash curler a fixed clamp member, a lip on the lower portion thereof, a resilient and stretchable movable clamp member, a resilient and stretchable casing or sheath over the movable clamp member, and means to engage the movable clamp member over the said lip.

9. In an eyelash curler a fixed clamp member, a lip on the lower portion thereof, a resilient and stretchable movable clamp member having its end connected adjacent the ends of the fixed clamp member, a resilient and stretchable casing over the movable member, and means whereby the movable clamp member may be moved to engage over the said lip.

10. In an eyelash curler a fixed clamp member, a lip over the lower portion thereof and a resilient and stretchable clamp member adapted to be removably engaged over said lip.

11. In an eyelash curler a fixed clamp member, a lip on the lower portion thereof, and a resilient and stretchable clamp member having its ends anchored adjacent the ends of the fixed clamp member, said resilient member being adapted to be removably engaged over said lip.
